H. G. KELLY

ROOFING STRIP

Filed Nov. 27, 1925

UNITED STATES PATENT OFFICE.

HARRY G. KELLY, OF OMAHA, NEBRASKA.

ROOFING STRIP.

Application filed November 27, 1925. Serial No. 71,553.

This invention relates to attenuated strips adapted to be applied as a covering for the roofs or sides of buildings, and has for one of its objects to provide ornamental strips which 5 may be produced without undue waste of material. Another object is to provide roofing strips of such form that they may be quickly applied to a building and will present an attractive appearance. The invention includes a new and useful arrangement of recesses and wings for the strips and means for 10 securing the superposed strips of a row to the strips of a lower row in such a manner that they will be effectively held to a roof and the 15 injury or displacement from effects of wind or storms, as well as leakage, will be prevented. Another feature is to provide strips of such form and arrangement that nails and metallic fasteners used will not be visible and 20 will be protected from the weather after the strips have been applied.

With the foregoing objects in view, and others to be mentioned hereinafter, the invention presents a novel and useful construction, combination and arrangement of parts as described herein and claimed, and as illustrated in the accompanying drawing, where- 25 in,

Fig. 1 is a plan view of one of the roofing strips. Fig. 2 is a plan view showing superposed strips. Fig. 3 is a plan view showing a part of a sheet cut to form the strips. Fig. 4 is a plan view showing a wing and notches formed in a strip. Fig. 5 is a transverse section through the strips on line 5—5 of Fig. 2. Figs. 6, 7 and 8 are detail views on an enlarged scale. Fig. 6 is a plan view of a metallic fastener. Fig. 7 is a side view of the fastener shown in Fig. 6. Fig. 8 is a sectional view on line 8—8 of Fig. 2. Fig. 9 is a section on line 9—9 of Fig. 1, on an enlarged scale. Fig. 10 shows a modified form for a metallic fastener.

Referring now to the drawing in which like reference characters indicate like parts, the herein described roofing strips 10 are of such form that when disposed one upon another as shown in Fig. 2, they will present to view surfaces 11 which are uniform in shape and size and ornamental in appearance.

In order that the surfaces 11 will be hexagonal in plan when the strips 10 are disposed in overlapped relation, said strips at one of their longitudinal edges are incised to provide outwardly convergent wings 12 and intermediate, outwardly divergent recesses 13, the

area of each wing corresponding to the area of each recess. However, the exact number of wings 12 and recesses 13, arranged in alternation along one edge of a strip is not important, except that the length of the strips should not be too great for convenience of a workman when securing them to a building, or when crating them for shipment, and while the strip shown is preferred, I do not wish to limit myself to the number of wings and recesses for each roofing strip.

In order that the strips may be effectively secured to a building I provide metallic tie-strips or fasteners 14 for securing the wings 15 of an upper roofing strip to a lower roofing strip. Each wing at its end is provided with an extension *a*, best shown in Figs. 1 and 3, and each extension is bent to form a tab 15, best shown in Figs. 5 and 8, to lie beneath said wing.

Each metallic fastener 14 is disposed between a wing and the tab 15, and preferably it is secured to the tab, as by means of prongs *b* with which the fasteners are provided and which traverse the tabs, as best shown in Fig. 8. Also a modified form of fastener 20, shown in Fig. 10 might be attached to the lower side of the tab by means of prongs *b'*, bent upward for traversing the tab. However, the fasteners 14 may be secured to the tabs by any suitable means, and it is not necessary to operation that the fasteners be secured to the tabs, since each fastener is bent as indicated at *c* (Fig. 7.) adjacent to its ends, and is provided with end portions *d* disposed in a plane adjacent to the body of said fastener; and in operation each metallic fastener, when not secured to a tab, will be maintained in engagement with said tab since, as will be seen, its end portions *d* will be disposed beneath a lower roofing strip.

It will be understood that, in operation, the strips are disposed end to end, the wings 12 and recesses 13 being disposed in alternation throughout the length of a row, said strips being suitably secured to a roof or side of a building by use of nails 16. A second row of strips is then laid to overlap the strips of the first row and is secured in like manner, a third and other rows of strips being then applied.

By referring to Fig. 3 it will be seen that a standard sheet 17 may be incised to provide a plurality of roofing strips 10, each strip having wings 12 with extensions *a* without appreciable waste of material, apertures 18,

rectangular in plan, being formed adjacent to the ends of the wings.

While no mechanism is shown for use in incising sheets 17 to form the strips and apertures, it will be understood that this may be accomplished in the usual way, by moving the sheets between cutting rollers.

It will be seen that when the strips have been separated from the sheet 17, notches *e* 10 will be formed near the junction of the wings with the body of the roofing strip, each notch having an edge *f* disposed longitudinally of the strip to operate as a stop-member and having an edge *g* disposed transversely of the 15 strip to operate as a guide. Also, as best shown in Fig. 1, notches *e'* will be formed in the wings at the ends of the tabs *a*, said notches *e'* having edges *h* disposed approximately parallel with the edges *g*; and since 20 the distance between said edges *h* of notches *e'* is less than the distance between the edges *g* of the notches *e*, secondary recesses *k* will be formed as best shown in Fig. 8, between the edges *g* and *h* for receiving the curved parts *c* 25 of the metallic fasteners 14 when an upper strip has been disposed upon a lower strip.

It will be seen that the work of securing the strips to a roof in overlapped relation may be speedily accomplished, each strip of 30 an upper row having a sliding movement upon and transversely of the strips of a lower row, the curved parts *c* of the metallic fasteners engaging in the secondary recesses *k*, and the end-portions *d* of each fastener being 35 disposed beneath the lower strip.

According to the construction as shown and described, the tabs operate to reinforce the wings, and the metallic fasteners also reinforce the wings. Also the fasteners operate 40 to great advantage in securing the wings of an upper strip to a lower strip. It will be noted that the metallic fasteners are well protected since they are disposed for the most part beneath the wings of the upper strips and beneath the lower strips, the nails 16 being covered by the strips of an upper row.

When moving an upper strip for the purpose of securing it to a lower strip, the edges *g* operate as guides for the metallic fasteners 50 14, no particular attention of a workman being required for causing the parts to register correctly, and the upper strip may be moved until the edges *f* are engaged by the fasteners 14, said edges *f* operating as stop-members for preventing any further movement of said upper strip; and after the fasteners engage the edges *f*, said upper strip may be secured to the roof by use of the nails mentioned.

It is considered that it would be within the scope of the invention to enlarge the notches *e* by removing the edges *f* so that the edges *g* 60 would extend to the edges *m* between the wings of the strips, this being accomplished by incising the strips in alignment with the

intersecting, dotted lines *n* and *p* shown in Fig. 4.

If the notches *e* were thus enlarged each edge *m*, between the wings 12 would operate as a buffer or stop since the metallic fasteners 70 may have any suitable width, and may have such a width that they will engage the edges *m* to limit a movement in one direction of an upper strip when it is placed in position upon a lower strip.

Also while it has been stated that the edges *g* operate as guides for the metallic fasteners, this construction being preferred, it is considered to be within the scope of the invention to dispense with the notches *e*, the edges 80 *g* and the outwardly convergent edges of the wings operating as guides. It is appreciated, of course, that sufficient space should be provided at the ends of the tabs to permit the parts *d* to be disposed below a lower strip 10, and the recesses *k* provide this feature, but the length of the tabs may be decreased if desired so that the space between their ends and the edges of the wings would permit the ends *d* of the fasteners to be disposed below 90 a lower strip.

Furthermore it is considered that it would be within the scope of the invention to increase the length of the tabs 15 and to eliminate the recesses *k* by incising the wings along the lines *g* and *m* so that the length of the inner edge of the tab 15 would be approximately equal to the length of the edge *m*, and in the application of the superposed strips the transverse edges of the tab 15 would engage with edges *g* to prevent longitudinal misplacement, and the inner edge of the tab 15 would engage the edge *m* to limit the transverse motion of the superposed sheet, the tab 15 being in the same plane as the wings of 105 the lower strip, metallic fasteners 20 being attached to the lower side of tabs 15, their end-portions engaging the lower side of the adjacent strip to provide secure fastening of the wings of the superposed strip in the 110 manner hereinbefore described.

I claim as my invention, —

1. A roofing strip having an edge provided with spaced tabs having substantially complementary intermediate recesses, the upper side edges of said tabs being provided with right angular portions projecting into the recesses, the lower edges of said portions providing a stop, and at least part of the upper edges of said tabs being formed at substantially right angles to the said lower edge of said right angular portions to form guiding means, stiff fastening means carried by each tab having bent portions projecting laterally from the lower side edges of said tabs, whereby an overlying strip may be moved upwardly so that the outer part of the bent portions of its fastening means will engage beneath the tabs of an underlying strip while the other part of the bent portions will engage the said 130

guiding means and stop of said underlying strip.

2. A roofing strip having an edge provided with spaced tabs having substantially complementary intermediate recesses, the upper side edges of said tabs being provided with right angular portions projecting into the recesses, the lower edges of said portions providing a stop, and at least part of the upper edges of said tabs being formed at substantially right angles to the said lower edge of said right angular portions to form guiding means, stiff fastening means comprising a metallic band carried by each tab having bent portions projecting laterally from the lower side edges of said tabs, whereby an overlying strip may be moved upwardly so that the outer part of the bent portions of its fastening means will engage beneath the tabs of an underlying strip while the other part of the bent portions will engage the said guiding means and stop of said underlying strip.
3. A roofing strip having an edge provided with spaced tabs having substantially complementary intermediate recesses, the upper side edges of said tabs being provided with right angular portions projecting into the recesses, the lower edges of said portions providing a stop, and at least part of the upper edges of said tabs being formed at substantially right angles to the said lower edge of said right angular portions to form guiding means, stiff fastening means carried by an undeturned lower edge of each tab having bent portions projecting laterally from the lower side edges of said tabs, whereby an overlying strip may

be moved upwardly so that the outer part of the bent portions of its fastening means will engage beneath the tabs of an underlying strip while the other part of the bent portions of its fastening means will engage beneath the tabs of an underlying strip while the other part of the bent portions will engage the said guiding means and stop of said underlying strip.

4. A roofing strip having an edge provided with spaced tabs having substantially complementary intermediate recesses, the upper side edges of said tabs being provided with right angular portions projecting into the recesses to form a narrowed recess, the lower edges of said portions providing a stop, and at least part of the upper edges of said tabs being formed at substantially right angles to the said lower edge of said right angular portions to form guiding means, stiff fastening means carried by an undeturned lower edge of each tab having bent portions projecting laterally from the lower side edges of said tabs, whereby an overlying strip may be moved upwardly so that the outer part of the bent portions of its fastening means will engage beneath the tabs of an underlying strip while the other part of the bent portions will engage the said guiding means and stop of said underlying strip and the said undeturned lower edge will be received in said narrowed recess.

In testimony whereof, I have affixed my signature.

HARRY G. KELLY.
